CLAIM

The ornamental design for a reverse bent coupling, as shown and described.

DESCRIPTION

FIG. 1 is a perspective view of a reverse bent coupling showing my new design;

FIG. 2 is a front view thereof;

FIG. 3 is rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a front view thereof, in use condition.

The even-broken lines shown in the drawings illustrate unclaimed portions of the reverse bent coupling that forms no part of the claimed design. The long-dash short-dash line represents the bounds of the claimed design.
